By Thomas G. Orwig, Atty.

UNITED STATES PATENT OFFICE.

ALONZO C. NOVESS, OF ROCHESTER, NEW YORK.

PHOTOGRAPHER'S LIGHT-REGULATOR.

No. 882,838.

Specification of Letters Patent. Patented March 24, 1908.

Application filed August 8, 1907. Serial No. 388,047.

To all whom it may concern:

Be it known that I, ALONZO C. NOVESS, a citizen of the United States, residing at Rochester, in the county of Monroe and State 5 of New York, have invented a new and useful Photographer's Light-Regulator, of which the following is a specification.

My invention relates to the photographers light regulator for which Letters Patent No. 10 853,467 were granted to me May 14, 1907 and consists in combining with the main standard adjustable and detachable auxiliary curtains on curtain rollers as hereinafter set forth, pointed out in my claims and illustrated in the accompanying drawings, in which:

Figure 1 is a perspective view that shows how the adjustable curtain supports are detachably connected with the main standard 20 of the complete apparatus and curtains on rollers adjustably connected with the curtain supports as required for practical use. Fig. 2 is an enlarged transverse sectional view on the line *x x* of Fig. 1 and shows how 25 the curtain rollers are pivotally connected with the lower curtain support so that they can be extended at different angles relative to the adjustable support and the standard. Fig. 3 is a top view that shows how curtain 30 roller carriers are slidably and pivotally connected with the adjustable roller supports to be moved to and from the standard and extended therefrom at various degrees of angles at different times as required for focusing light upon a person before a camera advantageously. Fig. 4 is an enlarged view 35 of a pulley on the upper roller support and shows how the pulley is slidably and rotatably connected therewith and provided with 40 means for fastening a cord to the pulley as required for retaining the curtain elevated to different heights at different times.

The numeral 10 designates a portable base to which is fixed, preferably detachably, a 45 tubular standard 12 and in the upper end is an adjustable extension 13.

A bearer 14 is slidably, adjustably and detachably connected with the standard 12 and fastened thereto at any point of elevation 50 desired by means of a set screw 15 as shown in Fig. 1, or in any suitable way. A corresponding bearer 16 is connected in the same way with the upper end portion of the standard 12.

To lower bearer 14 is fixed a cross bar 55 17 for supporting a roller carrier 18 on each

of its end portions. Only one of said carriers is shown in Fig. 1 and consists of a straight length of sheet metal that is stiffened by upturned flanges 19 at its sides and bearings 60 20 at its ends for the journals on the ends of curtain rollers 21.

The roller carriers, 18, have longitudinal slots 22 in their centers and over the slots are placed flat pieces of sheet metal, 23, and bolts 65 24 extended down through all the overlying parts, as shown in Fig. 2, to pivotally and slidably connect them in such a manner that the carriers and curtains 25 on the rollers 21 can be readily moved towards the standard 12 70 or away from it and also set at any angle desired relative to the standard as required for regulating the transmission of light between the curtains to a person or persons or object before a camera. A nut 26 on the 75 lower end of the bolt 24 retains it in place.

To the upper bearer 16 is fixed a rod 27 and on the rod is a pulley 28 slidably and rotatably mounted thereon and the curtain 25 is connected with the pulley by a cord 29, 80 as shown in Fig. 1 in such a manner that the curtain can be raised and lowered by simply rotating the pulley as required to lengthen and shorten it between the pulley and the curtain and by sliding the pulley on the rod 85 27 the cord can be readily placed in perpendicular alinement with the bolt 24 and the center of the curtain 25.

The pulley 28 has an integral extension 30 and a thumb screw 31 seated in the extension 90 for locking the pulley fast on the rod 27 at any point desired for retaining the curtain, 25, at any point of elevation desired.

Having thus set forth the purposes of my invention and its construction and manner of use the practical operation and utility thereof is obvious.

What I claim as new and desire to secure by Letters Patent, is:

1. In a photographer's light regulator, a 100 standard fixed to a base, a bearer slidably connected with the standard, a cross bar fixed to said bearer and a roller carrier pivotally and slidably connected with the cross bar fixed to said bearer, to operate as set 105 forth.

2. In a photographer's light regulator, a standard fixed to a base, a bearer slidably connected with the standard, a cross bar fixed to said bearer, a roller carrier pivotally 110 and slidably connected with the cross bar fixed to said bearer, a longitudinal slot in the

roller carrier and a pivotal bolt extended through the slot and the cross bar, to operate as set forth.

3. In a photographer's light regulator, a standard fixed to a base, a bearer slidably connected with the standard, a cross bar fixed to said bearer, a roller carrier pivotally and slidably connected with the cross bar fixed to said bearer, a longitudinal slot in the roller carrier, a pivotal bolt extended through the slot and the cross bar, roller bearings at the ends of the roller carrier and a curtain roller mounted in said bearings, to operate as set forth.

15 4. In a photographer's light regulator, a standard fixed to a base, a bearer slidably connected with the standard, a cross bar fixed to said bearer, a roller carrier pivotally and slidably connected with the cross bar fixed to said bearer, a longitudinal slot in the roller carrier, a pivotal bolt extended through the slot and the cross bar, roller bearings at the ends of the roller carrier, a curtain roller mounted in said bearings, a curtain fixed to the roller and means to elevate and suspend the curtain at different points of elevation, to operate as set forth.

5. In a photographer's light regulator, a standard fixed to a base, a bearer slidably connected with a cross bar fixed to said bearer, a roller carrier pivotally and slidably connected with the cross bar fixed to said bearer, a longitudinal slot in the roller carrier, a pivotal bolt extended through the slot and the cross bar, roller bearings at the ends of the roller carrier, a curtain roller mounted in said bearings, a curtain fixed to the roller, a rod fixed to the upper end portion of the standard, a pulley slidably and rotatably mounted on the rod to elevate and suspend the curtain at different points of elevation, to operate as set forth.

6. In a photographer's light regulator, a standard fixed to a base, a bearer slidably connected with the standard, a cross bar fixed to said bearer, a roller carrier pivotally

and slidably connected with the cross bar fixed to said bearer, a bearer adjustably connected with the upper end portion of the standard and a rod fixed to the bearer to extend horizontally, to operate as set forth.

7. In a photographer's light regulator, a standard fixed to a base, a bearer slidably connected with the standard, a cross bar fixed to said bearer, a roller carrier pivotally and slidably connected with the cross bar fixed to said bearer, a bearer adjustably connected with the upper end portion of the standard, a rod fixed to the bearer to extend horizontally, a pulley slidably and rotatably mounted on the rod and means to fasten the pulley to the rod, to operate as set forth.

15 8. In a photographer's light regulator, a standard fixed to a base, a bearer slidably connected with the standard, a cross bar fixed to said bearer, a roller carrier pivotally and slidably connected with the cross bar fixed to said bearer, a bearer adjustably connected with the upper end portion of the standard, a rod fixed to the bearer to extend horizontally, a pulley slidably and rotatably mounted on the rod, an integral extension at one end of the pulley and a set screw in the extension to fasten the pulley to the rod, to operate as set forth.

20 9. An improvement in a photographer's light regulator, comprising a standard, a bearer at the lower part of the standard, a cross bar on the end of said bearer, roller carriers on the cross bar, curtain rollers on the roller carriers, curtains on the rollers, a bearer at the top portion of the standard, a rod fixed to the bearer, pulleys slidably and rotatably mounted on the rod, cords fixed to the pulleys and connected with the curtains and means to fasten the pulleys to the rod, arranged and combined to operate as set forth.

75 ALONZO C. NOVESS.
